UNITED STATES PATENT OFFICE.

FREDERIC WILLIAM CHARLES SCHNIEWIND, OF EVERETT, MASSACHUSETTS, ASSIGNOR TO THE UNITED COKE AND GAS COMPANY, OF CHARLESTON, WEST VIRGINIA, A CORPORATION OF WEST VIRGINIA.

METHOD OF TREATING AND UTILIZING GASES.

No. 820,525.

Specification of Letters Patent.

Patented May 15, 1906.

Application filed January 22, 1900. Serial No. 2,313.

To all whom it may concern:

Be it known that I, FREDERIC WILLIAM CHARLES SCHNIEWIND, a citizen of the United States of America, residing in Everett, in the county of Middlesex, in the State of Massachusetts, have invented a certain new and useful Improvement in Methods of Treating and Utilizing Gases, of which the following is a true and exact description, reference being had to the accompanying drawing, which forms a part thereof.

My invention relates to the treatment and utilization of gases generated in the process of carbonizing fuels in closed externally-heated retorts, and has for its object the saving and utilization of illuminants contained in such gases, which have heretofore been to a large extent wasted; and my invention consists, broadly speaking, in a process the first step of which is accomplished by separating the rich and poor gases given off in the distillation process in substantially the manner described in my prior patent, No. 627,595, dated June 27, 1899, and then subjecting the fraction of the gases relatively poor in illuminants to a treatment by means of which the illuminants are removed from it for independent use or sale.

My invention further consists in hereinafter-described modifications and additions to the general process indicated above.

In practice I have found it highly advantageous to utilize the illuminants extracted from the poorer fraction of gases for increasing the illuminating power and value of the richer fraction of gas, by preference adding the illuminants extracted to such richer fraction without concentration or condensation; but this process of utilizing the illuminants forms the subject-matter of my Patent No. 684,590, dated October 15, 1901, and my present invention is designed to cover the process of recovering the illuminants irrespective of the utilization subsequently made of them.

As to the nature and distribution of illuminants I would state that bituminous coal, which is the most important raw material for the manufacture of gas, produces "coal-gas" when subjected to dry distillation in closed retorts. While the quality and illu-

minating value of the gas varies considerably with the character of the coal, about sixty-five to eighty per cent. of the illuminating value of the gas is due to benzol and its homologues and about twenty to thirty-five per cent., to the presence of hydrocarbons of the olefine series, (ethylene and its homologues.)

A very large proportion of benzol produced during the distillation of the coal remains in the gas after it leaves the condensing plant. Of the total benzol yielded ninety per cent. was found in the gas and only ten per cent. in the tar. Again, a certain coal with which I have worked and subjected to dry distillation in a modern by-product coke-oven yielded about ten thousand cubic feet of gas per gross ton, and of this there were approximately five thousand cubic feet (the first fraction) available as a surplus after applying the remaining five thousand cubic feet (the second fraction) for heating the coking-ovens. I also ascertained that in the first fraction were contained about sixty-two per cent. of the total illuminants produced, including benzol and its homologues and ethylene and its homologues, while the second fraction contained about thirty-eight per cent., and it will be understood that my present process contemplates the utilization of the first or richer fraction for illuminating-gas or otherwise and the extraction from the second or poorer fraction of the greater part of its illuminants before it is utilized for heating the coking-ovens or for other purposes or allowed to go to waste.

If the illuminants contained in the richer and poorer fractions of the gas were present in the same proportion with respect to each other, a treatment to extract the illuminants from the poorer fractions would be, to say the least, of problematical value, because, while benzol and its homologues can readily be extracted from gas, ethylene and its lower homologues are gases at ordinary temperatures, which, practically speaking, cannot be extracted from the gas. In the process of dry distillation, however, by far the largest portion of ethylene and its homologues are driven off at lower temperature during the first stages of the operation and are therefore found in the

richer fraction of the gases, in which fraction they constitute an important percentage of the total illuminants, while in the poorer fraction of the gases given off at higher temperature during the later stage of the distillation these non-separable illuminants form but an inconsiderable percentage, by far the greater part consisting of benzol and its homologues. Thus, for example, I have found that in the 10 gas where the poorer fraction showed 9.5 candle-power 8.8 of this was due to benzol and its homologues—that is to say, of the total available candle-power 92.5 per cent. was due to illuminants which could be and were conveniently extracted under practicable conditions. With these facts in view it will be readily understood that my process, which provides for the practical commercial saving and utilization in the most economical manner of practically all the illuminants contained in the gases given off during distillation, is one of considerable commercial value.

With regard to the removal of the illuminants from the second fraction of the gas I may state that several methods are applicable, depending upon the nature of the illuminants to be extracted. Several such methods are known, and I do not wish to be understood as limiting myself to the employment of any particular method except where such particular method is expressly referred to in the claims. Generally speaking, the different methods in use are of two characters—first, the cooling process according to which the benzol or its homologues are condensed by exposing the gas to low temperature, and, second, the absorption process, in accordance with which the benzol is extracted from the gas by exposing such gas 40 to the action of oils or other materials having the property of absorbing benzol. The tar-oil employed may, for instance, conveniently be creosote-oil—to wit, the fraction of coal-tar distillation going over between 240° and 45 270° centigrade. In this latter or absorption process comparatively cold tar-oil is generally employed as the solvent, and in my preferred method I subject the second fraction of gas, preferably after treatment in the 50 condensing-house, to a scrubbing with tar-oil in what I call the "benzol-washer," the oil on entering the washer having a low percentage of benzol and on leaving it about twelve to fifteen per cent. of benzol. I then 55 carry said oil into a benzol-still, in which the benzol or the greater part of it present is thrown off as a distillate and afterward treated in any usual or convenient manner for commercial utilization. By preference, however, I subject the oil to a fractional distillation, first driving off the bisulfid of carbon, which it has also absorbed and which can be readily separated before the benzol is driven

off, because the boiling-point of the bisulfid of carbon is 47.0 centigrade, while the boiling-point of benzol is 80.4° centigrade. The boiling-point of toluol is 111.0° centigrade, and the boiling-point of xylool is from 137.5° to 142.0° centigrade. After passing through the benzol-still I cool the tar-oil down to the proper degree and again pass it through the benzol-washer, the process of extracting the benzol being thus conveniently made continuous.

Reference being now had to the drawing, 75 which diagrammatically represents a plant suitable for the practice of my invention, and in which is indicated a bank of coke-ovens, A' A² A³ indicating separate ovens, each provided, as shown, with two outlets for gas—one, a, for the richer gas and the other, a', for the poorer gas. These outlets are connected by pipes a², each having situated in it a controlling-valve a³ with either the rich-gas main (indicated at C') or the poor-gas main (indicated at C).

B indicates the condensing-house of the gas-plant, which I have indicated as divided into two separate systems—B', in which the poor gas is treated, and B², in which the richer gas is treated. The various washing and condensing devices usually employed in such condensing-houses are indicated at B³, B⁴, E, and E'. B⁵ indicating suction-blowers situated, as shown, between condensers B⁴ 95 and washers E.

C⁴ indicates the main for the richer fraction of gas leading from the condenser system B², and C⁵ indicates a main for the poorer fraction of gas leading from the condenser system B' to the benzol-washer, (indicated at F.) This washer has at its top a distributing device for tar-oil (indicated at F') and is filled with perforated trays (indicated at F²) above its lowermost chamber F³, into which the pipe C⁵ enters.

C², leading from the top of the washer, is the conduit through which the poorer fraction of gas, robbed of its illuminants, is conducted, either to heat the ovens A or to any other point of utilization or storage.

f is the outlet-pipe for tar-oil, leading from the washer F to a reservoir H.

G is a reservoir for cool tar-oil, connecting by a pipe g with the distributor F' and through a pipe k having situated in it a force-pump L', connected with the oil-reservoir K.

h is a pipe having in it a force-pump L, leading from the reservoir H to the bisulfid-of-carbon still, (indicated at O,) which still connects, by means of pipe h', with the benzol-still I, and by means of the pipe o with the condensing-coil P², situated in the condensing-tank P, p, and p', indicating inlet and outlet pipes for water. Coil P² connects, as shown, through a pipe p², with a reservoir

Q, in which the bisulfid of carbon is collected. The benzol-still I is divided into separate chambers in the usual way by partitions I², having flanged openings, as indicated at I³, over which are secured flanged caps I⁴. It is heated by a steam-pipe I⁵, forming coils, as indicated at I⁶, in the lower chambers of the still, I⁸ indicating the exhaust for the steam.

I⁶ indicates the collecting-chamber for the benzol-vapor at the top of the still from which leads the benzol-conduit C³, which may pass to any convenient place of utilization, condensation, or concentration.

i indicates the exhaust-pipe for the oil freed of its illuminants, said pipe leading into a cooler J, having a chamber J⁴ at top connected, by means of pipes J⁶, with the chamber J⁵ on its bottom, the pipes J⁶ passing through a chamber J³, into which cold water 20 is run through the pipe J⁷, leaving it through the pipe J². The cool tar-oil leaves the cooler J through the pipe j, which leads to the reservoir K, from which, as already indicated, it is drawn into the supply-tank G.

25 In operation the coal to be coked is charged in the oven A' A², &c., and during the earlier stages of the coking operation while the ovens are giving off rich gas the valves a³ are opened, connecting the ovens with the main C', the 30 gases passing through the condensing-house B² and then main C⁴ to a place of use or storage. During the later stages of the coking operation the valves a³, connecting the ovens with the main C', are closed and those connecting them with the main C opened, the 35 poor gases passing through the condensing-house B' and thence by main C⁴ to the benzol-washer F, through which they pass upward, escaping through main C², by which 40 they are conducted to the furnace-chambers (not shown) for heating the oven. The tar-oil for the washer F is supplied to it from tank G, flowing down through pipe g to the distributor F' and passing through the partitions F² to the chambers F³ and thence by pipe f to tank H. From tank H the oil, with absorbed illuminants, is drawn through pipe h by pump Z, passing to the bisulfid-of-carbon still O and thence by pipe h' to the benzol-still I, the bisulfid of carbon driven off 45 in still O passing by pipe o to the condenser-worm P² in cooling-tank P and thence by pipe p² to storage-tank Q. The benzol is distilled off from the tar-oil in still I, escaping 50 through pipe C³ to a place of use or storage, (not shown,) the oil passing down through pipe i to the cooler J and thence by pipe j to storage-tank K, whence it is drawn through pipe k by pump L' to tank G.

60 Having now described my invention, what I claim as new, and desire to secure by Letters Patent, is—

1. The method of utilizing the gases gener-

ated in carbonizing carbonaceous fuels in closed externally-heated retorts, which consists in drawing off the richer gases generated in the first part of the carbonizing process for separate uses as illuminating-gas or otherwise, said fraction of gas containing not only the larger percentage of total illuminants but 65 also a larger relative percentage of the more gaseous illuminants, then drawing off the poorer gases generated during the later stages of the carbonizing operation into separate receptacles, said gases having a larger relative percentage of extractable illuminants and treating said poorer fraction for the removal of its said more condensable illuminants. 75

2. The method of utilizing the gases generated in carbonizing carbonaceous fuels in closed externally-heated retorts, which consists in drawing off the richer gases generated in the first part of the carbonizing process for separate uses as illuminating-gas or otherwise, said fraction of gas containing not only the larger percentage of total illuminants, but also a larger relative percentage of the more gaseous illuminants, then drawing off the poorer gases generated during the later 85 stages of the carbonizing operation into separate receptacles, said gases having a larger relative percentage of extractable illuminants, treating said poorer fraction for the removal of its said more condensable illuminants, and then utilizing said poorer gases 90 after their condensable illuminants have been extracted, for heating the gas-generating retorts. 95

3. The method of utilizing the gases generated in carbonizing carbonaceous fuels in closed externally-heated retorts, which consists in drawing off the richer gases generated in the first part of the carbonizing process for separate uses as illuminating-gas or otherwise, said fraction of gas containing not only the larger percentage of total illuminants, but also a larger relative percentage of the more gaseous illuminants, then drawing off the poorer gases generated during the later 105 stages of the carbonizing operation into separate receptacles, said gases having a larger relative percentage of extractable illuminants, washing said poorer gases with oil in order to 110 separate the more condensable illuminants and removing said extracted illuminants by distillation. 115

4. The method of utilizing the gases generated in carbonizing carbonaceous fuels in closed externally-heated retorts, which consists in drawing off the richer gases generated in the first part of the carbonizing process for separate uses as illuminating-gas or otherwise, said fraction of gas containing not only the larger percentage of total illuminants but 120 also a larger relative percentage of the more

gaseous illuminants, then drawing off the poorer gases generated during the latter stages of the carbonizing operation into separate receptacles, said gases having a larger 5 relative percentage of extractable illuminants, subjecting said poorer gases to a condensing and washing treatment in order to

remove tars and other impurities and then to a washing treatment with oils in order to remove its more extractable illuminants.
